SUCTION CLEANER

William D. Sellers, Glen Ellyn, and Alfred G. Gross, Wilmette, Ill., assignors to The Hoover Company, North Canton, Ohio, a corporation of Ohio

Application August 23, 1939, Serial No. 291,518

25 Claims. (Cl. 15—6)

The present invention relates to suction cleaners in general and more particularly to an improved nozzle height adjusting means in a suction cleaner. More specifically the invention comprises a suction cleaner in which the surface-contacting nozzle mouth and cleaner agitator are automatically positioned in proper operating relationship to a surface or to a surface covering undergoing cleaning under all conditions of cleaner operation.

It is an object of the present invention to provide a new and improved suction cleaner. It is another object of the invention to provide a new improved nozzle height adjusting means in a suction cleaner. Another object of the invention is to provide a new and improved agitator-positioning means in a suction cleaner. A still further object of the invention is to provide a suction cleaner embodying automatic nozzle height and agitator-height-adjusting means to compensate for variations in surface coverings undergoing cleaning. A still further object of the invention is to provide a feeler-controlled nozzle height adjustment which automatically positions the cleaner nozzle in the proper operating relationship to a covering undergoing cleaning. A further object of the invention is to provide a suction-operated automatic nozzle height adjustment in which a surface-contacting feeler controls the nozzle position. Still another object of the invention is to provide a suction cleaner in which a floating sub-nozzle is automatically positioned to the proper relationship to a surface covering undergoing cleaning by means including a surface position feeler. A still further object of the invention is to provide a sub-nozzle including surface-contacting lips and a driven agitator which is automatically positioned relative to a surface covering undergoing cleaning to the optimum position by means controlled by a surface-contacting feeler or gauge. Still another object of the invention is to provide an automatic nozzle height adjustment which is feeler-operated and which includes electrical means to vary the nozzle height. These and other more specific objects will appear upon reading the following specification and claims and upon considering in connection therewith the attached drawings to which they relate.

Referring now to the drawings in which preferred embodiments of the present invention are disclosed, and in which the same reference character refers to the same part throughout:

Figure 1 is a side view of a suction cleaner embodying the present invention with certain

parts broken away and shown in section in the inoperative relationship and upon a bare floor;

Figure 2 is a partial bottom view of the cleaner illustrated in Figure 1;

Figure 3 is an enlarged view of the suction-operated bellows of the air motor;

Figure 4 is a view similar to Figure 1 but illustrates the cleaner positioned upon a bare floor in operation;

10 Figure 5 is a view similar to Figure 4 but with a cleaner positioned upon a surface covering and in operation;

Figure 6 is a section upon the line 6—6 of Figure 4 and illustrates the nozzle-lifting bellows and its connection to the ambulatory body-supporting chassis;

Figure 7 is a longitudinal section through the feeler-controlled valve which connects the lower chamber of the air motor to atmosphere;

20 Figure 8 is a section upon the line 8—8 of Figure 7;

Figure 9 is a side elevation of a cleaner constructed in accordance with the second preferred embodiment of the invention and in which a sub-nozzle construction is movably mounted relative to the remainder of the cleaner body and is automatically positioned by a feeler-controlled mechanism as in the first embodiment;

25 Figure 10 is a bottom view of the cleaner illustrated in Figure 9;

Figure 11 is a view of the cleaner constructed in accordance with the second embodiment of the invention in operation upon a bare floor;

30 Figure 12 is a front view of the cleaner nozzle of the second embodiment of the invention with a portion of the front wall broken away to show the sub-nozzle positioned therein;

35 Figure 13 is a partial side elevation of a suction cleaner embodying a third preferred embodiment of the invention, with certain parts broken away and shown in section, the cleaner being positioned upon a bare floor and in the inoperative relationship;

40 Figure 14 is a bottom view of the cleaner constructed in accordance with the third embodiment of the invention;

45 Figure 15 is a transverse cross section through the feeler-controlled switch of the third embodiment;

50 Figure 16 is a section through the cut-out switch mounted upon the cam shaft;

55 Figure 17 is a diagrammatic disclosure of the electrical circuit of the cleaner of the third embodiment, the parts being related as in Figures 13 and 15.

Suction cleaners provided with manually-operable nozzle height adjusting means have been made and sold for many years. They have the inherent weakness that when the operator, after setting the machine properly for a surface covering of one type, later moves the machine onto a covering of a different type he frequently fails to reset the adjustment. The result is that the cleaner is improperly positioned for operation upon this second covering and inefficient operation results. A more recent development has been the automatic nozzle height adjustment. These prior automatic adjustments, however, embodied the inherent weakness that the adjustment of the cleaner supporting means was dependent upon the length of the pile and its stiffness. No account was taken by such adjustments of the variations in density or tightness of weave of the rug back, nor of the stiffness of the rug. These latter elements are just as important as any present in determining the response of the surface covering undergoing cleaning to the nozzle suction. Also it has been impossible to accommodate all these factors perfectly for they vary indiscriminately in different coverings. While the automatic adjustment means might be designed to be accurate in positioning the nozzle at the proper height relative to a surface covering undergoing cleaning where that covering had one pile height, one pile thickness and one back weave, the variation of one of those factors, such as the tightness of weave of the rug back or the stiffness thereof might render the adjustment means unsatisfactory.

In the automatic nozzle height adjustment means constructed in accordance with the present invention the adjustment of the nozzle and of the cleaner agitator is made so as to be entirely independent of the weight of the cleaner, the stiffness of the surface covering pile, the density thereof, or the tightness of weave or stiffness of the rug back. The only condition which controls the operation of the nozzle height adjustment constructed in accordance with the present invention is the relationship of the covering undergoing cleaning to the surface-contacting portion of the nozzle and the agitator. If the relationship is the optimum no adjustment takes place. If it is any other relationship adjustment automatically follows and continues until the optimum relationship is established. This result is obtained by the provision of a feeler which is adapted to contact the supporting surface below the cleaner nozzle and below the cleaner agitator. This feeler member has one optimum position which corresponds to the optimum nozzle and agitator height adjustment. If properly positioned the surface covering undergoing cleaning will hold this feeler member at its optimum position and no adjustment takes place. If the relationship of the nozzle and agitator relative to the surface covering varies so that the feeler moves from its optimum position, it rides at all times upon the supporting surface in the cleaner operation, automatic adjustment instantly follows and the height position of the nozzle and agitator is changed until the feeler is again moved by the covering undergoing cleaning to its optimum position.

Referring again to the drawings and to Figures 1 to 8, inclusive, a suction cleaner embodying the first preferred embodiment of the invention is illustrated. The cleaner is seen to include an ambulatory U-shaped chassis 1 which is sup-

ported by front and rear wheels 2 and 3, respectively. The cleaner handle 4 is pivotally connected directly to the chassis 1.

The cleaner body includes a nozzle 6 having surface-contacting front and rear lips 7 and 8, respectively, a fan chamber 9 to the eye 10 of which the nozzle 6 is interiorly connected by a passageway 11, and an exhaust outlet 12 of the fan chamber which is provided with bag-sealing manually operable means 13. A motor housing 15 encloses an unshown driving motor, and is positioned immediately above the fan chamber 9 and exhaust outlet 12. The motor shaft 16 extends downwardly through the fan chamber where it carries the suction-creating fan 17 and is formed at its lower end within the air passageway 11 as a driving pulley. The body also includes appearance skirts 14 which extend rearwardly from the ends of the nozzle 6 to conceal partially the supporting chassis 1 and the supporting wheels 2 and 3.

The cleaner body is pivotally supported upon the ambulatory chassis 1 by a pivotal connection 18 immediately forward of the rear supporting wheels 3. About this pivot point the cleaner body, together with the filtering bag 20, pivots to raise and lower nozzle 6 relative to the chassis, there being supporting springs 22 between the arms of the chassis 1 and the overlying skirts 14 which carry the weight of the cleaner body forwardly of the pivotal connection. Each of these springs encircles a post 23 which extends downwardly from the cleaner body skirt 14 and which is adapted to abut the chassis, as illustrated in Figure 4, 35 with the cleaner nozzle in its lowermost position. A restraining bolt 24 passes through an aperture 25 in each arm of the chassis and into the bottom of depending post 23 with its headed end spaced therefrom to provide a lower stop to determine, with the end of post 23, the possible angular movement of the cleaner body relative to the chassis.

Positioned within the nozzle casing 6 is an inner nozzle casing 27 the top and front walls of which are spaced from the casing 6 to provide a space therebetween. The air passageway 11 in fact opens directly into this inner nozzle casing 27 and the top, bottom and side walls are formed integral therewith as is the front nozzle lip 7. The rear lip 8 is formed integrally with the removable bottom plate 28 of the passageway 11.

Rotatably mounted within the inner nozzle casing 27 is a rotatable agitator 30 which is formed with a cylindrical body upon which are provided elongated helically extended rigid beater elements 31 and axially extending flexible brush elements 32. A pivoted latch member 33 at each end of the agitator removably retains it within the nozzle and a power-transmitting belt 34 connects it to the lower end of the motor drive shaft.

Within the space between the outer nozzle casing 6 and the inner nozzle casing 27, and in front of the fan chamber 9, is positioned an air motor which provides the power by which the nozzle 6 is raised and lowered. This air motor is indicated generally by the reference character 35 and is seen to comprise a V-shaped bellows construction having rigidly mounted top wall 36 and a rigidly mounted bottom wall 37 which extends the length of the nozzle. An intermediate movable piston wall or plate 38 is pivoted at 39 at the angle of the V, there being enclosing, collapsible, flexible air-impervious seals 40 joining the peripheral edges of the walls 36, 37 and 38. These seal members 40 are accordions-

like, as is clearly illustrated in Figures 1 and 4, so that the intermediate plate 38 is permitted a range of angular movement between the top and bottom walls of the bellows.

At the ends of the air motor the plate 38 is provided with projecting shoulders 41 to each of which pivotally connects a pivoted arm 42 the lower end of which is pivotally connected to the ambulatory chassis 1. The relationship is such that the tilting angular movement of the cleaner body relative to the chassis is accompanied by the pivotal movement of the plate or piston 38 of the air motor, that member being given a range of movement adequate to accommodate the permitted angular pivotal movement of the cleaner body.

The upper and lower chambers formed in the air motor upon the opposite sides of the plate or piston 38 are internally connected by conduits 44 and 45 to the interior of the fan chamber immediately inside of the eye 16 thereof, and at a point which is in substantial alignment with the eye of the fan chamber and the point of cut-off thereof which is indicated at 46. It has been found that when so located suction is always present in the pipes 44 and 45 and accordingly within the chambers of the air motor in all operating relationships of the cleaner which includes operation in which the cleaner nozzle is sealed to a surface covering undergoing cleaning and also operation in which the nozzle is entirely unsealed and the flow of air through the cleaner is unrestricted. The suction available to the motor chambers by the suction-creating means of the cleaner is the same.

A feeler member 48 is pivotally mounted at 49 and extends rearwardly between the nozzle lips 7 and 8 and below the rotary agitator 30. This element is positioned below the portion of reduced diameter of the agitator which serves as the pulley to seat the driving belt 34 and is movable upwardly to a point within the confines of the circle described by the surface-contacting beating elements 31. Forwardly of its pivot point the surface-contacting feeler 48 is pivotally connected to a vertically extending rod 50 which carries a fixed abutment shoulder 51 which is at all times urged upwardly by a helical coil spring 52 the lower end of which seats upon an L-shaped seat 53 mounted upon the forward wall of the interior nozzle casing 27. The force exerted by the spring 52 at all times urges the feeler 48 downwardly and with a predetermined force. Upward movement of the feeler 48 toward the agitator is accomplished only by the contact therewith of an underlying surface undergoing cleaning, as illustrated in Figure 5. The lowermost position of the feeler is determined by the abutment of the forward end thereof with the forward face of the front wall of inner nozzle 27, as indicated at 47 in Figure 4, and in this position the feeler just contacts a bare supporting surface.

To the lower motor chamber is interiorly connected, by an air passageway 55, a valve chamber 56 which is open to atmosphere at its one end by an aperture 57 and which has its opposite end closed by a counterbored screw plug 58. Extended into the valve chamber 56 through the open end 57 thereof and seated in screw threaded relationship therewith is a cylindrical valve chamber wall 60 which is formed with elongated axially extending ports 61 which open into the space between the wall 60 and the surrounding chamber 56. Rotatably mounted within the

chamber wall 60 is a rotatable valve 62 which is provided with air seals 63 at its opposite ends in the form of enclosing gaskets and also with longitudinally extending ports 64 which are similar in size and shape to the ports 61 in the enclosing valve chamber wall 60. The stem of valve 62 extends through the counterbored chamber-closing plug 58, there being a sealing gasket therearound indicated at 66 which is compressed by the stem-enclosing nut 67. The outer end of the valve stem non-rotatably carries the valve arm 68, which is itself pivotally connected to the upper end of the plunger rod 59. It is clear that the pivotal movement of the feeler 48 resulting in the vertical displacement of the plunger rod will cause the angular rotary movement of the valve arm 68 and will result in the rotation of the valve 62 within its enclosing chamber wall 60.

20 The function of the surface covering feeler 48, the air motor 35 and the connections between the air motor and the chassis is to provide automatically the proper adjustment of the nozzle and agitator relative to a surface undergoing cleaning. 25 If that surface is a floor covering efficient cleaning demands that it be lifted from the supporting surface by the nozzle suction into contact with the nozzle lips and the rotary agitator in the manner illustrated in Figure 5. If a bare floor 30 is being cleaned, it is desirable that the nozzle be lowered until the lips closely approach the floor and the agitator brush elements 32 extend into contact therewith in the manner illustrated in Figure 4, the beater elements having a smaller 35 radial extension will not contact the bare floor. The manner in which the supporting surface feeler 48 and the air motor cooperate properly to position the nozzle and agitator will now be described. 40 Let it be assumed that the cleaner is positioned upon a bare floor with the motor turned off and the cleaner inoperative, as illustrated in Figure 1. Upon the energization of the cleaner motor, which is accomplished by the operator turning 45 on the usual cleaner switch of any ordinary type and which is not shown in the drawings, the motor begins to rotate and the shaft 16 drives the suction-creating fan 17. Immediately there 50 results a flow of air into the cleaner nozzle as a result of the suction created by the fan 17. This suction is effective at the point of connection interiorly of the fan chamber of the conduits 44 and 45 and immediately air is drawn from both chambers of the air motor into the fan chamber. The upper motor chamber is sealed to the exterior and air is exhausted therefrom immediately creating a sub-atmospheric pressure. With the cleaner positioned as shown in Figure 1 the feeler is in its lowermost position 55 and below its optimum position, being forced downwardly by the spring 52. The valve 62 is in a wide open relationship to permit the pressure in the lower motor chamber to approach atmospheric and to exceed greatly the sub-atmospheric pressure of the upper chamber. This difference of pressure acting upon the two sides of the plate 38 forces that element upwardly within the motor but as the arms 42 connect it to the chassis the net result is that the forward end of the cleaner is drawn downwardly and against the upward force of the springs 22. This downward movement will continue until the depending posts 23 abut the chassis 1, as illustrated in Figure 4, it being assumed that the cleaner remains upon a bare floor. When the motor is

turned off and the suction dissipates, the springs 22 will again raise the forward end of the cleaner to the position illustrated in Figure 1.

When the machine is so adjusted upon a bare floor as just described the nozzle lips 7 and 8 are positioned closely adjacent the surface and the agitator 30 is brought sufficiently close thereto that the flexible brush elements 32, which have a greater radial extension than the rigid beater elements 31, are able to contact and sweep that floor. Foreign material positioned thereon is dislodged by the brushes and is swept up into the air passageway and conveyed by the fan to the filtering bag 20 attached at the rear of the machine.

Let it be supposed that the machine is pushed from the bare floor, and in the adjustment just described, onto a surface covered by a carpet or rug, as illustrated in Figure 5. The sink of the supporting wheels into the pile of the covering and the resultant contact of the covering with the feeler 48 will cause that element to be pivoted upwardly into the nozzle against the resisting force of coil spring 52. This angular movement of the feeler results in the angular movement of the valve arm 68 with the attendant rotation of valve 62 which moves its ports 64 partially out of alignment with the chamber ports 61 thereby cutting down the flow of atmospheric air into the valve chamber and so into the lower motor chamber. Immediately a pressure drop is effected therein as less atmospheric air is available and as the same suction is always provided by the suction-creating fan. The pressure in the lower motor chamber being reduced, the body-supporting coil springs 22 are able to force the forward end of the cleaner body upwardly. This adjustment continues until the feeler element 48 assumes its optimum position which it does when the covering is lifted into optimum relationship with nozzle and agitator. At that time the flow of air into the lower motor chamber through the valve 62 provides a differential pressure across the plate or piston 38 which is just sufficient to counterbalance the lifting effect of the coil spring 22. A state of equilibrium will exist and the surface covering will be properly positioned relative to the nozzle lips and to the agitator for it is the surface covering which positions the feeler 48.

If the machine is positioned while inoperative upon a surface covering then the operation is substantially that described in connection with the bare floor, except that the nozzle moves downwardly into contact with the surface covering to make the necessary contact of the feeler member therewith and thereafter the lifting operation just described takes place.

The construction has the advantage that no manual attention is necessary and the machine automatically repositions itself upon variation in surface coverings.

Referring now to Figures 9 to 12, inclusive, the second preferred embodiment of the invention is illustrated. This embodiment differs primarily from that first described in that the ambulatory chassis 1 of the first embodiment has been eliminated and instead the supporting wheels 2 and 3 are mounted directly to the cleaner body and no relative vertical movement takes place therebetween. There is again provided the pivoted handle 4, the outer nozzle casing 6, the front and rear surface-contacting lips 7 and 8, the fan chamber 9 having its eye 10 and formed with an exhaust outlet 12 to which

the bag 20 is removably secured by manually operable nuts 13.

As distinguished from the first embodiment the inner nozzle casing or sub-nozzle 27, which includes the air passageway 11 and the surface-contacting lips 7 and 8, is pivotally mounted at the rear of the fan chamber by a bracket 75 upon a pivotal connecting pin 76 carried by the supporting bracket 78 of the rear wheels 3. As in the first embodiment the air passageway 11 is closed by a removable bottom plate 28 which also is pivoted with and forms a part of the sub-nozzle construction. The upper wall of the air passageway 11 immediately below and adjacent the eye 10 of the fan chamber 9 is formed with a circular opening 79 which is resiliently connected to the eye 10 by a flexible, collapsible conduit 80 of material such as rubber. The entire sub-nozzle construction 27 and the rotatable agitator 30 carried thereby are adapted to move up and down about the pivot point 76 and within the main body of the machine, the front lip 7 being provided with a vertical extension 82 which rides against the inner face of the forward wall 25 of the outer nozzle casing 6 and is provided with a slot 83 which cooperates with a pin 84 carried by that outer nozzle casing to determine the limits of angular movement of the sub-nozzle. Coil springs 86 at each end of the nozzle connect the rear face of the sub-nozzle 27 to the underside of skirt 14 of the main nozzle casing and at all times exert a lifting force thereon which normally lifts the sub-nozzle to its uppermost position with the cleaner inoperative. Springs 86 have sufficient force to lift the sub-nozzle together with a surface covering undergoing cleaning which is suction-sealed thereto but is adapted to be overcome by the pressure differential existing within the air motor which is also present in this embodiment of the invention.

The air motor 35 in this second embodiment of the invention is again positioned forwardly of the fan chamber 9 and between the inner nozzle casing 27 and the outer nozzle casing 6 but in this instance is mounted directly upon the top of the former and is movable therewith. The upper and lower chambers thereof are again connected by the conduits 44 and 45, respectively, to that portion of the interior of the fan chamber 9 adjacent the eye 10 thereof at which there is always substantially the same suction available. The conduits 44 and 45 in this embodiment should be sufficiently flexible to permit unhindered the vertical movement of the sub-nozzle with which they move at their forward ends. The feeler 48 is pivotally mounted as before and is here movable with the sub-nozzle construction, as is the valve chamber 56 and the interconnecting parts which are the same as in the first embodiment. The link 42 which connects to the movable piston or plate 38 in the present embodiment, however, connects directly to the underside of the main casting which includes the nozzle 6 and fan chamber 9 rather than to the supporting chassis as in the first embodiment. As the sub-nozzle is adapted to rise and fall relative to the main casing of the machine, it is obvious that when so connected the arm 42 is capable of transmitting the force exerted upon the piston 38 to cause the movement of the sub-nozzle relative to the main casing.

The operation of the cleaner constructed in accordance with the second embodiment of the invention greatly resembles the first embodiment. The feeler 48 is, as in the first embodiment, adapt-

ed to control the flow of air into the lower motor chamber thereby varying the differential pressure existing upon the piston or plate 38. If the feeler 48 is in its lowermost position the valve 62 is opened wide and the pressure within the lower motor chamber is much greater than that in the upper chamber and the piston 38 is forced upwardly. This has the effect of forcing the sub-nozzle downwardly about the pivot point 10, such action being permitted by the flexible conduit 80. In Figure 11 the machine is illustrated in the operating position having been lowered to the extent permitted by the pin 84 and slot 83. If the machine were positioned upon a surface covering the sub-nozzle would be lowered until the feeler element made contact therewith at which time the feeler element would be pivoted upwardly, the valve 62 would be partially closed, the pressure differential existing across the piston 38 would be reduced until a state of equilibrium would finally be reached in which the lifted weight of the surface covering undergoing cleaning in contact with the nozzle lips 1 and 8 combined with the differential pressure existing across the plate 38 of the air motor would equal the lifting force exerted by the springs 66. The automatic adjustment feature of this second embodiment duplicates that of the first construction, the essential difference being that in this case only the surface-contacting portions of the nozzle and the agitator are adjusted vertically to obtain the proper cleaning action whereas in the first embodiment the entire cleaner was moved relative to a supporting chassis.

Referring now to Figures 12 to 17, inclusive, the third preferred embodiment of the invention is illustrated. This embodiment closely resembles the first described embodiment with the exception that the air motor thereof has been replaced by an electrical motor. A U-shaped ambulatory chassis 1 is again movably supported by front and rear wheels 2 and 3, respectively, and pivotally carries the handle 4 by which the cleaner is actuated. The outer nozzle casing 6 is formed in the same main casing with the fan chamber 9 and again houses the sub-nozzle 27 in fixed relationship, the latter being interiorly connected by the air passageway 11, including the removable bottom plate 28, to the eye 16 of the fan chamber 9. In this embodiment the sub-nozzle or interior nozzle casing 27 is not movable relative to the main casing including the fan chamber 9 and nozzle casing 6, as in the second embodiment, but instead the entire cleaner body is pivotally connected at the pivot point 19, as in the first embodiment, for pivotal movement relative to the chassis.

The pivoted cleaner body is supported at its front end, in the manner of the first embodiment, by coil springs 22 which extend between the body and the chassis 1, there being a depending post 23 with its screw threaded and spaced bolt 24 which limits the pivotal movement of the body relative to the chassis. In the present embodiment the coil springs 22 at all times urge the cleaner nozzle upwardly relative to the chassis to an extent permitted by the rotatable cams 90 positioned at each side of the nozzle. These body-carried cams are spring-pressed upwardly into contact with overlying abutment shoulders 91 on the chassis 1. To rotate the positioning cam 90 there is provided an electric motor 92 which is suitably mounted on the underside of the cleaner body below the skirt 14 and which is connected to the shaft 99 of cam 90 by suitable reduction

gears indicated generally at 94. The rotation of the motor 92 in one direction causes the cam to rotate in a particular direction to raise or lower the nozzle, while motor rotation in the opposite direction has the opposite effect. The direction of motor rotation is controlled by the cooperation of the surface-contacting pivoted feeler 48. The feeler 48 in the present embodiment is provided with a rigid vertical extension 96 which is pivotally connected at its upper end to a lever arm 97 of the current-controlling switch indicated generally at 98. A leaf spring 99 exerts a force to move the feeler member downwardly and replaces the coil spring used in the previous embodiments. The switch 98 is seen to comprise an insulating casing 100 which is seated upon the inner nozzle casing 27 and in which a sliding actuator 101 operated by the lever arm 97 is itself connected to and actuates the movable snap action contacts 102 and 103 which are movable between contacts 104, 105 and 106, 107, respectively, as illustrated in Figures 15 and 17. The movable contacts 102 and 103 are of the over-center type and the movement of the actuator 101 to the extreme right causes both contacts to assume the position illustrated in Figure 15, which is also illustrated diagrammatically in Figure 17. Movement of the actuator 101 to its mid-position places movable contacts 102 and 103 in contact with the central contacts 105 and 106, a position which represents the motor-off condition.

As can be seen in Figure 17 stationary contacts 104, 105, 106 and 107 are divided into parts a and b which are adapted to be interconnected in each instance by the movable contacts. In Figure 17 the incoming conductors 108 and 109 are seen to connect directly to the armature 111 of the main cleaner motor and to its field 111 in series therewith, there being a current-controlling manually operable switch 112. The cam-actuating motor 92 is seen to be connected in parallel with the main cleaner motor, lead 108 extending to one terminal of the armature 92a while the lead 109, after passing through the manual control switch 112, connects directly to the feeler-operated switch 98. More specifically, lead 109 connects directly to the central stationary contacts 105a and 106a, the contacts 105b and 106b being connected directly to opposite sides of the motor field winding 92b. Contacts 104b and 107b connect to opposite sides of motor field 92b and to the same sides thereof as contacts 105b and 106b, respectively. Of the two remaining contacts 104a and 107a, 107a connects directly to the armature 92a by the lead 125. Contact 104a is connected directly, by the lead 123, to the stationary arcuate contact ring 114 of the switch 115, the movable contact 116 of which is connected to the lead 126, and so directly to the contact 107a, by the lead 124.

Movable contact 116 of switch 115 is mounted upon the shaft 99 of cam 90, as is best shown in Figure 16, and is connected thereto by the shaft-carried pin 119 which seats in a circumferentially extending slot 120 of limited extent in the contact. A torsion spring 117 on the shaft 99 abuts and urges the contact 116 in a counter-clockwise direction, as viewed in Figure 16. A raised portion is provided on the collector ring 114 at its end, as indicated at 118, and an insulation section 122 is positioned between that portion and the stop 121. The purpose of the raised portion 118 and the spring 117 is to give a snap-operation to the switch and this is now explained.

If it be assumed that the movable contact 116 is upon the ring 114 and against the raised portion 118 in particular, counterclockwise movement of the shaft 89 under the operation of the motor 92 will effect no movement of the contact 116 until the pin 119 has abutted the end of slot 120 and has forced the contact over the raised portion 118. The spring 117 will then move contact 116 with a snap action from contact 114 and over insulation 122 and against stop 121. Current is thus interrupted with a quick break. The closing action will result from the contact of pin 119 with the opposite side of slot 120 and the resultant contact movement upon continued shaft movement. This will not be a snap action but this is not necessary on the circuit-closing stroke.

The operation of this last embodiment of the invention is as follows: The relationship illustrated in the Figures 13, 15 and 17 of the drawings is that in which the cleaner nozzle and agitator are positioned at their greatest height above the surface covering or supporting surface. The cam 90 has been so rotated that the supporting coil springs 22 have lifted the forward end of the body to its maximum height. The surface-contacting feeler 48 is pivoted downwardly to its lowermost position and the lever 96 thereof has moved the switch lever arm 97 to its righthand position and the actuator 101 of the switch 98 has been moved thereby to the position illustrated in Figure 15. The movable contacts 102 and 103 are positioned as shown in Figures 15 and 17 and the motor 92 is operated.

The circuit of the height adjusting motor is as follows: The current-carrying lead 108 connects to the armature 92a on one side, the other side thereof being connected through the leads 125 and 124 to the movable contact 116 of switch 115. The circuit then includes the stationary contact 114, the lead 123, stationary contact 104 and movable contact 102 to the field 92b. The opposite side of the field is connected to stationary contact 106b which is connected by the movable contact 103 to contact 106a and the incoming current-carrying lead 109. Current thus flows through the height-adjusting motor and causes the rotation of the height adjusting cam 90. As it rotates it forces the body downwardly by exerting a force against the overlying shoulder 81 of the chassis 1. This downward movement continues until, if the cleaner is positioned upon a bare floor, the movable contact 116 of the switch 115 moves off the end of the contact ring 114 by the continued rotation of the cam shaft 89, the separation of contacts 114 and 116 being accomplished by a snap action because of the presence of the spring 117.

The opening of the adjusting motor circuit by the switch 115 occurs when the nozzle has been lowered into cleaning relationship to a bare floor. However, if the cleaner were positioned upon a surface covering the lowering would have stopped when the feeler member 48 contacted that covering and was pivoted upwardly thereby to its optimum position. In moving to that position the lever arm 96 would have pivoted sufficiently to move the lever arm 97 and actuator 101 would have caused movable contact 102 to move into contact with stationary contact 105. The circuit of the motor field 92b would thereupon have been opened, movable contacts 102 and 103 being seated upon contacts 105 and 106 which are short circuited at 105a and 106a.

If, because of the weight of the rug, or because of excessive suction in the cleaner, the carpet is

raised too high or extends too far into the nozzle mouth and too close to the agitator, the feeler 48 will be pivoted above its optimum position. This will result in further movement of the actuator 101 to the left as viewed in Figure 15 and the movable contact 103 will be moved with a snap action from contact 106 to contact 107. Current through the motor field 92b will then flow in the opposite direction. In the first instance, with the contacts 102 and 103 positioned as illustrated in Figure 17 current could enter from lead 109, pass through contact 106 and movable contact 103 to the right side of field 92b and thence in the direction to the left and to movable contact 102 and thence to the switch 115. In this last relationship, however, in which movable contact 103 seats upon stationary contact 107 and movable contact 102 is seated upon stationary contact 105, the lead 109 will be connected to the movable contact 102 through the lefthand side of the field and current will move to the right therethrough.

Variations in the position of the surface covering undergoing cleaning relative to the nozzle in this last embodiment of the invention, as in the preceding embodiments, effect variations in the angular position of the feeler element 48. This change in position effects change in the position of contacts 102 and 103 of switch 98 which in turn causes the motor 92 to rotate in one direction or the other to raise or lower the nozzle. The functional result is substantially the equivalent of the first two embodiments but is accomplished by electrical means rather than by suction.

We claim:

1. In a suction cleaner, the combination of a body having suction-creating means and a nozzle communicating with said suction-creating means, supporting wheels for said body, said wheels and nozzle being capable of limited relative vertical adjustment for regulating the height of the nozzle with respect to the floor covering being cleaned, and means including a prime-mover actuated by said suction-creating means and operative to support said nozzle normally out of contact with the surface of said floor covering, air-conducting means connecting said prime-mover to said suction-creating means and controlling means for said prime-mover including a floor contacting element responsive to variations in the position of the floor covering relative to said nozzle.

2. In a suction cleaner, the combination of a body including suction-creating means and a nozzle, wheels supporting said body and adapted for vertical adjustment relative to said nozzle, and means including a prime-mover mounted on said body and actuated by the suction created by said suction-creating means to maintain said nozzle normally at an optimum relationship to the surface of the floor-covering being cleaned, and means including surface-contacting means movable relative to said nozzle and responsive to variations in the position of the floor covering relative to said nozzle for regulating the effective suction actuating said prime-mover.

3. In a suction cleaner, the combination of a casing including suction-creating means and having a nozzle at its forward end, supporting wheels at the front and rear ends of said casing, said front wheels being mounted for limited vertical adjustment relative to said casing, a pressure-responsive element mounted on said casing and having operative connection with said adjustable front wheels, air-conducting means connecting said element to said suction-creating means, said

pressure-responsive element operating to maintain said nozzle normally in a predetermined relationship to a surface covering undergoing cleaning, and means for controlling the effective suction acting on said pressure-responsive element comprising a valve connecting the same with the atmosphere and having a lever adapted to contact the floor covering and to shift with changes in the position thereof relative to said nozzle, whereby said valve acts to relieve the suction in said pressure-responsive element and allows said nozzle to be adjusted accordingly.

4. In a suction cleaner, the combination of a casing including suction-creating means and having a nozzle at its forward end, front and rear wheels supporting said casing, a frame carrying the wheels and having pivotal mounting on said casing, a bellows member mounted on said casing and operatively connected with said wheel supporting frame, air-conducting means connecting said bellows to said suction-creating means said bellows being responsive to the suction created by said suction-creating means to maintain said nozzle normally in contact with the surface covering undergoing cleaning, and means for varying the effective suction acting on said suction-responsive element, comprising a valve leading from said bellows member to the atmosphere and having a lever adapted to contact the surface covering undergoing cleaning and shiftable with variations in the position of the covering below the nozzle relative thereto to position the nozzle for effective cleaning action thereon.

5. In a suction cleaner, the combination of a casing including suction-creating means and having a nozzle at its forward end, supporting wheels at the front and rear ends of said casing, a frame pivotally mounted on said casing and carrying said wheels, a pressure-responsive element mounted on said casing and having operative connection with said wheel carrying frame, said pressure-responsive element communicating with said suction-creating means and subject to the suction thereof to maintain said nozzle at a predetermined height above the floor surface, tension means acting to prevent the lowering of said nozzle toward the floor surface, and means for controlling the effective suction acting on said pressure-responsive element comprising a valve leading from said element to the atmosphere, and a lever operatively connected with said valve and shiftable in contact with the floor covering to permit atmospheric pressure to relieve the suction and allow said spring to effect the adjustment of said nozzle to the position of the floor covering being cleaned.

6. In a suction cleaner, the combination of a casing including a nozzle and suction-creating means communicating with said nozzle, a wheeled frame supporting said casing having pivotal connection therewith whereby said casing may be tilted to raise or lower said nozzle, a spring acting to maintain said casing normally in a position of maximum nozzle height, a bellows mounted on said casing and operatively connected with said wheeled frame, said bellows being connected with said suction-creating means and normally capable of overcoming the tension of said spring, a valve connecting said bellows with the atmosphere and having a spring-pressed lever adapted to contact the floor covering and operative to relieve the suction in said bellows to effect the adjustment of said

70 nozzle under spring pressure into optimum relationship with the covering being cleaned.

7. In a suction cleaner, the combination of a casing including a nozzle and suction-creating means communicating with said nozzle, a wheeled frame supporting said casing and having pivotal connection therewith whereby said casing may be tilted to raise or lower said nozzle, a compression spring acting to elevate said casing to a position of maximum nozzle height, a bellows mounted on said casing and including a movable member operatively connected with said wheeled frame, said bellows communicating with said suction-creating means upon both sides of said movable member, a valve opening from said bellows on one side of said movable member to the atmosphere and having a spring-pressed floor-covering-contacting lever acting to open said valve with a floor covering undergoing cleaning displaced below its optimum position relative to said nozzle whereby the force of suction acting on one side of said movable bellows member is relieved to enable the pressure on the opposite side thereof to effect the lowering of said nozzle against spring pressure to a height correct for the particular floor covering being cleaned.

8. In a suction cleaner, a nozzle including a surface-contacting mouth, suction-creating means connected to said mouth, height-adjusting means to raise and lower said mouth relative to a surface undergoing cleaning, an air motor connected to said height-adjusting means to actuate same and including two chambers, a movable piston in said motor separating said chambers, conduits connecting said chambers to said suction-creating means, valve means connecting one of said chambers to atmosphere, and a surface-contacting feeler at said mouth movable with changes in height relative thereto of a surface covering undergoing cleaning connected to said valve to control the flow of atmospheric air into one of said chambers and so to control the pressure differential existing across 45 said piston.

9. In a suction cleaner, a nozzle including a surface-contacting nozzle mouth, suction-creating means connected to said mouth, a surface-contacting feeler movable with said mouth and adapted to be displaced relative thereto by contact with a surface covering, ambulatory supporting means, means pivotally mounting said nozzle on said supporting means for vertical movement relative to a surface covering undergoing cleaning, means to raise and lower said nozzle relative to said supporting means, means including an air motor connected to said suction-creating means to actuate said last-mentioned means, and means operated by said feeler 60 to control said air motor.

10. In a suction cleaner, a nozzle having a mouth adapted to contact a surface covering undergoing cleaning, means movably supporting said nozzle for movement over said covering means including a prime mover to raise and lower said nozzle mouth relative to said supporting means and to a supporting surface, and control means for said prime mover including surface-contacting means positioned at said nozzle 65 to gauge the position of a surface covering undergoing cleaning relative to said mouth to energize said prime mover with said surface covering positioned in other than a predetermined optimum relationship to said mouth.

11. In a suction cleaner, a nozzle having a

mouth adapted to contact a surface covering undergoing cleaning, means movably supporting said nozzle for movement over said covering, means including a prime mover to raise and lower said nozzle mouth relative to said supporting means and to a supporting surface, and control means to control the movement of said prime mover including a surface-covering-positioned gauge in said mouth adapted to be raised or lowered relative thereto by that portion of a surface covering undergoing cleaning positioned immediately below said nozzle.

12. In a suction cleaner, a nozzle having a mouth adapted to contact a surface covering undergoing cleaning, means movably supporting said nozzle for movement over said covering, means including a prime mover to raise and lower said nozzle mouth relative to said supporting means and to a supporting surface, control means including means to effect movement of said prime mover in either of two directions or to fix said prime mover stationary, said control means also including a covering-feeler movably mounted relative to said nozzle and spring-biased into covering-contacting position with that portion of the surface covering contacted by the nozzle and lifted thereby, said feeler directly determining the position of a surface covering undergoing cleaning relative to said nozzle mouth and by its own position determining the operation of said control means.

13. In a suction cleaner, a suction nozzle including a mouth, suction-creating means connected to said mouth, an agitator in said nozzle adapted to contact a surface covering undergoing cleaning at said mouth, means to drive said agitator, a movable feeler at said nozzle to contact that portion of a surface covering undergoing cleaning positioned immediately below and adapted to be lifted by the suction of said nozzle said feeler being mounted for movement upon variations in the vertical relationship of said nozzle mouth and agitator relative thereto, means to raise and lower said nozzle mouth and agitator, and means controlled by said feeler to actuate said last-mentioned means upon movement of said feeler.

14. In a suction cleaner, suction-creating means, a suction nozzle connected to said means, a movable feeler in the mouth of said nozzle adapted to contact an underlying surface covering undergoing cleaning, and movable therewith upon variations in the vertical position thereof relative to said nozzle mouth, means to raise and lower said nozzle, and an air motor internally connected to said suction-creating means and operatively connected to said last-mentioned means to actuate same and controlled by said feeler.

15. In a suction cleaner, a nozzle having a mouth, suction-creating means connected to said nozzle and adapted to create a reduced pressure therein to effect the lifting of an underlying surface covering undergoing cleaning upwardly into contact with said mouth, a covering-contacting feeler in said nozzle mouth to determine the position of said covering relative thereto, means to raise and lower said nozzle mouth, an air motor connected to said suction-creating means to actuate said last-mentioned means, and means connecting said feeler to said motor to control the operation thereof upon feeler movement.

16. In a suction cleaner, a body including a nozzle, a vertically displaceable surface-contacting sub-nozzle within said nozzle, suction-creat-

ing means connected to said sub-nozzle, feeler means displaceable relative to said sub-nozzle and positioned as to contact that portion of a surface covering undergoing cleaning positioned below said sub-nozzle, means to raise and lower said sub-nozzle, and means controlled by said feeler means to actuate said last-mentioned means.

17. In a suction cleaner, a body including a nozzle, a vertically displaceable surface-contacting sub-nozzle within said nozzle, an agitator carried by said sub-nozzle, suction-creating means connected to said sub-nozzle, feeler means extended adjacent said agitator and displaceable relative thereto by that portion of the surface covering undergoing cleaning which is positioned under and adapted to be lifted by the suction in said sub-nozzle, means to raise and lower said sub-nozzle relative to said body, and means controlled by said feeler means to actuate said last-mentioned means.

18. In a suction cleaner, a body including a nozzle, a vertically displaceable surface-contacting sub-nozzle within said nozzle, suction-creating means connected to said sub-nozzle, feeler means positioned as to be displaceable relative to said sub-nozzle by contact with that portion of a surface covering undergoing cleaning positioned under and adapted to be lifted by the suction in said sub-nozzle, means including a motor inside said body having relatively movable parts connected to said body and to said sub-nozzle to move the latter vertically, and means controlled by said feeler means to control the operation of said motor.

19. In a suction cleaner, a body including a nozzle, a vertically displaceable surface-contacting sub-nozzle within said nozzle, suction-creating means connected to said sub-nozzle, feeler means displaceable relative thereto by contact with a surface covering undergoing cleaning, means including an air motor carried by said sub-nozzle inside said body and having relatively movable parts certain of which are connected to said body to move said sub-nozzle relatively to said body, said air motor being connected internally to said suction-creating means, and means controlled by said feeler means to control the operation of said motor.

20. In a suction cleaner, a vertically displaceable surface-contacting element, a feeler vertically movable with said element and movable relative thereto to determine the contact relationship of a surface undergoing cleaning with said element, suction-creating means including a fan chamber having an eye and a cut-off, means to raise and lower said surface-contacting element, an air motor to actuate said last-mentioned means, conduit means connecting said air motor to the interior of said fan chamber adjacent the eye thereof and at a point tangent to said eye and between said eye and said cut-off, and feeler-operated means controlling said motor.

21. In a suction cleaner, a surface-contactible element vertically adjustable above and below an optimum position with respect to a surface covering undergoing cleaning, a gauge positioned to gauge the height of that portion of the surface covering contacted by said element and vertically displaceable with said element and movable relative thereto between limits and upon both sides of an optimum position it assumes when the element is in its optimum position, means to raise and lower said element, and means responsive to the position of said gauge to actuate said last-mentioned means to raise or lower said element.

22. In a suction cleaner, a surface cleaning means, ambulatory means movably supporting said cleaning means, adjustable means mounting said cleaning means on said ambulatory means for vertical movement relative to the plane of a surface covering undergoing cleaning and including an electric motor, switch means to control said motor, a gauge adjacent, vertically movable with, and movable relative to said cleaning means to determine directly the position of a surface covering undergoing cleaning relative to said cleaning means under a force received from that portion of a surface covering undergoing cleaning positioned immediately opposite said cleaning means, said gauge being movable under said force above and below an optimum position, and means connecting said gauge to said switch to position the latter in accordance with the position of said gauge.

23. The construction recited by the preceding claim characterized in that a second switch is provided to control said motor and including relatively movable parts, and means to actuate said parts to open said switch to stop said motor upon said cleaning means reaching a lowermost position as in the cleaning of bare floors.

24. In a suction cleaner, a body, an agitator carried by said body adapted to make contact with a surface covering undergoing cleaning, means to actuate said agitator, a movable feeler adjacent said agitator to contact that portion of a surface covering undergoing cleaning positioned below said agitator, said feeler being mounted for movement upon variations in the vertical relationship of said agitator relative to said covering, means to raise and lower said agitator, and means controlled by said feeler to actuate said last-mentioned means upon movement of said feeler.

25. In a suction cleaner, a body, an agitator carried by said body adapted to make contact with a surface covering undergoing cleaning, means to actuate said agitator, a movable feeler adjacent said agitator to contact that portion of a surface covering undergoing cleaning positioned below said agitator, said feeler being mounted for movement upon variations in the vertical relationship of said agitator relative to said covering, a reversible electric motor to raise and lower said agitator, and means actuated by said feeler to control said motor.
